UNITED STATES PATENT OFFICE

JOHN H. WITASCHEK, OF DENVER, COLORADO, ASSIGNOR OF ONE-THIRD TO FRED N. HOLLAND, AND ONE-THIRD TO PAUL J. BREHM, BOTH OF DENVER, COLORADO

CURTAIN FASTENER

Application filed January 19, 1932. Serial No. 587,509.

This invention relates to fastenings for the suspension of traverse drapes and curtains. Drapes or curtains of this type are commonly suspended in pairs from a horizontal pole by means of rings or hooks that are sewn along the upper edges of the drapes or curtains, and a cord or cords attached to the rings or hooks at the meeting edges of the curtains, are passed over pulleys, as a means 5 for moving the curtains together or for separating them by pulling them apart.

An objection in the use of equipment of this type has been found in the fact that during movement of the curtains, the rings 15 or hooks will move sideways against the parts to which they are attached, thereby causing a binding resistance to the movement of the cords and interfering with the free movement of the curtains along the pole. 20 It is an object of the present invention to prevent such lateral displacement of the rings or hooks, by the provision of simple means for holding them at right angles to the curtains and to the axis of the pole from which 25 the curtains are suspended.

Traverse curtains of the character above mentioned often gap at their meeting edges when pulled together and it is in many instances desirable to avoid such gapping by 30 lapping the curtains in their light-excluding position.

It is another object of the invention to provide one or more so-called master-rings, which at the edges of the curtains have means 35 to insure positive lapping movement of the curtains when pulled together, without obstruction or interference of the moving parts.

An embodiment of the invention has been shown in the accompanying drawings in 40 which like reference characters indicate corresponding parts throughout the views, and in which

Figure 1 represents a face view of the upper portions of a traverse curtain equipment 45 with the curtains shown in separated relation,

Figure 2, a similar view showing the curtain closed together in lapping relation to each other,

Figure 3, a top view of the equipment as 50 illustrated in Figure 2,

Figure 4, a perspective view of the master-fastenings of lapping curtains, made in accordance with my invention,

Figure 5, a face view of a hook-fastener of the improved type, 55

Figure 6, a side view of the fastener shown in Figure 5,

Figure 7, a face view of a hook-fastener of modified construction,

Figure 8, a side view of the same, 60

Figures 9, 10 and 11, respectively, a face view, a side view and a rear face view of another modified form of the invention, and

Figures 12 and 13, face and side views of 65 still another modification.

Referring first to Figures 1 to 4 of the drawings, the master-fastenings 5 and 6, sewn at the edges of curtains 8 and 9 suspended from a pole 10, each consist of a ring-shaped suspension-member 12 slidably supported by the pole. 70

Each fastener is provided with aligned vertical legs 13 and 14 in the planes of their respective rings, and with aligned arms 15 projecting laterally at right angles to the 75 legs. As shown at 18, the legs and arms are looped at their extremities.

The fastenings are sewn to the curtains by means of their legs and arms and it will be apparent that the legs and the arms co-operate to prevent movement of the rings in either direction and thereby prevent the rings from binding upon the pole or from buckling or tilting against the curtains. The arms 80 15 prevent any lateral displacement of the rings and, therefore, are an essential feature of the invention.

The master-fastening 6 has one of its arms 16 elongated and offset as at 17, to provide 85 a space into which the corresponding arm of the other fastener may enter, as is best shown in Figures 3 and 4. It will be readily understood that with fastenings of this type sewn oppositely at the edges of the curtains as illustrated in Figures 1 and 2, the curtains 90 when drawn together by means of the ropes 19, will slide along the pole to a position in which their edge-portions overlap. Gapping 95 at the meeting edges of the curtains is thus prevented and the offset 17 of the arm 16 100

of the one fastening, provides a space into which the edge-portion of the other curtain may freely enter.

5 The curtains are suspended from the pole by a number of spaced fasteners 20 in addition to the master fasteners hereinbefore described.

10 Figures 12 and 13 show such fasteners as composed of a ring 21 slideable on the pole, a single leg 22 extending downwardly therefrom, and laterally projecting arms 23 equivalent to the arms 15 of the master fastenings 5 and 6.

15 In Figures 9 to 11, a hook 24 takes the place of the ring of the before-described forms.

Legs 25 extend oppositely from the hooks and lateral arms 26 project at right angles to the legs as before.

20 In practise, the curtains to which the fasteners are applied, are suspended from the curtain pole by means of the hooks instead of rings.

25 In certain types of equipment, rings 27 are placed on the pole independent of the fastenings, as shown in Figures 5 to 8 inclusive. The rings are provided with small hangers 28 to admit hooks 29 of the fastenings. The form of fastenings illustrated in Figures 5 and 6 differs from that of the fasteners of Figures 7 and 8, mainly in the addition of a comparatively long upwardly extending leg 30 which aids materially in holding the fasteners in fixed position with relation to the curtains.

30 The poles 10 and the rings 27 have been shown in broken lines in Figures 5 to 13, as not being a part of the invention.

What I claim and desire to secure by Letters Patent is:

40 1. A curtain fastener comprising a suspension member, a leg extending in the plane thereof, and arms projecting laterally from the suspension member at substantially right angles to said plane, an arm of the fastener 45 being offset to provide a space for the admission of an arm of a corresponding fastener.

2. A curtain fastener comprising a suspension member having means whereby the member may be secured to a curtain and an offset arm projecting laterally from the member.

50 3. A curtain fastener comprising a suspension member, and arms projecting laterally from said member, one arm being offset with regard to the other arm to admit the arm of a complementary fastener, and the offset arm being elongated to effect sufficient overlapping of curtains supported by said fasteners.

55 4. A curtain fastener comprising a suspension member, and laterally projecting arms substantially at right angles to the plane of said member, each arm projecting outwardly directly from said member in oppo-

site directions, and the arms being adapted to be separately secured to the curtain.

5. A curtain fastener comprising a suspension member, and a laterally projecting arm, a portion of the arm being positioned on 70 said member and the remainder of the arm being offset with regard to said portion and with regard to said member.

6. A curtain fastener comprising a suspension member composed of a single piece 75 providing projecting legs and having a loop between said legs, and laterally projecting arms positioned substantially at the junction of the legs, said legs and arms being adapted to be secured to a curtain. 80

7. A curtain fastener comprising a suspension member adapted to be suspended beneath a curtain rod, an elongated leg on said member extending vertically above the curtain rod, and arms beneath the rod extending laterally with relation to the leg. 85

8. A curtain fastener comprising a ring for a curtain rod, a leg depending from the ring, and laterally projecting arms positioned across said leg beneath the rod, said legs and arms being adapted to be secured to a curtain. 90

In testimony whereof I hereunto affix my signature.

JOHN H. WITASCHEK.
